STEP CONSTRUCTION FOR EMBROIDERY MACHINES

Anthony Majorie, Fort Lee, N. J.

Application August 1, 1942, Serial No. 453,157

1 Claim. (Cl. 228—47)

This invention relates to new and useful improvements in a step construction for embroidery machines and the like.

Heretofore, when working on high machines having high parts which could not be reached while standing on the ground, the operators positioned benches, boxes and other similar articles in front of the machine on which to stand to reach the high parts. This invention proposes overcoming this objection by providing the machine with a step construction having a normal inoperative raised position and which may be lowered when needed to form a step upon which the operator may stand to reach the high parts of the machine.

Another object of the invention proposes to characterize the step construction by a support for attachment on the machine to support spaced brackets upon which a step is pivotally mounted in a manner to be movable from an operative horizontal position to an inoperative vertical position and vice versa.

It is a further object of the invention to limit pivoting of the step between the horizontal operative position and an upwardly slightly rearwardly inclined in a manner to retain its inoperative vertical position against the force of gravity.

Still another object of this invention proposes to characterize the step construction by a pair of steps pivotally supported to move in unison with the lower step being slightly to the front of the top step when the steps are in their horizontal position in a manner to permit the operator to walk up the steps to reach high portions of the machine.

A still further object of the invention proposes the construction of a step construction for embroidery machines which are simple and durable and which may be manufactured and sold at a reasonable cost to be applied as standard equipment on new machines or to be applied to machines now in use.

For further comprehension of the invention, and of the objects and advantages thereof, reference will be had to the following description and accompanying drawings, and to the appended claim in which the various novel features of the invention are more particularly set forth.

In the accompanying drawings forming a material part of this disclosure—

Fig. 1 is the schematic illustration of an embroidery or the like machine having a step construction in accordance with this invention.

Fig. 2 is an enlarged vertical sectional view taken on the line 2—2 of Fig. 1.

Fig. 3 is an enlarged detailed view of a portion of Fig. 1.

Fig. 4 is a plan view of a portion of Fig. 1.

Fig. 5 is an enlarged detailed view of another portion of Fig. 1.

Fig. 6 is a schematic illustration of an embroidery or the like machine having a step construction in accordance with a modification of this invention.

10 Fig. 7 is an enlarged end elevational view looking in the direction of the line 7—7 of Fig. 6.

Fig. 8 is an enlarged detailed view of a portion of Fig. 6.

Fig. 9 is a plan view of Fig. 8.

15 The step construction, according to this invention, is to be used on an embroidery machine or the like which is schematically illustrated by the dot and dash lines 10 on the figs. The step construction includes a pair of spaced posts 11 arranged vertically of the height of the machine 10. The bottom of each post 11 continues into a foot 12 which engages the floor upon which the machine 10 rests.

20 A support 13 is extended between the posts 11. The support 13 is formed of tubular stock having a square cross-section and is attached to the front of the machine by bolts 14. The bolts 14 extend through the back wall of the support 13, and the front wall of the support 13 is formed with enlarged openings 15 aligned with the bolts 14 for facilitating the engagement of the bolts 14 in position.

25 Spaced brackets 16 are mounted in position upon the front wall of the support 13 by means of bolts 17. Each bracket 16 has a forwardly extending vertical lug 18. An arm 19 is mounted on the front end of each of the lugs 18. Each of the arms 19 is formed of L-shaped material which is inverted to have a vertical portion 19^a and a horizontal portion 19^b continuing from the top edge of the vertical portion 19^a.

30 The rear end of the vertical portion 19^a of each arm 19 is bifurcated to have the front end of the lug 18 engaged therebetween. A bolt 20 is engaged through the overlapped portion of the lug 18 and the bifurcated rear end of the vertical portion of the arm 19 to pivotally support the arm on the lug 18. The bottom of the bifurcated rear end of the vertical portion 19^a is closed by means of a wall 21 to engage the bottom edge of the lug 18 in the horizontal position of the arm 19 to limit the arm against pivoting downwards past the horizontal.

35 A step 22 is engaged across the top faces of certain adjacent arms 19. As shown there is

preferably a step 22 for each three arms 19. These steps 22 are constructed of wood and are secured in position upon the horizontal portions 13^b of the arms 19 by screws 23.

On the inner face of each vertical post 11 beneath the steps 22 a step 25 is mounted. This step 25 is constructed of a piece of material 26 having an edge secured to the post 11 by a bolt 27. The piece of material 26 is retained in a horizontal position on the post 11 by a diagonal bracket 28. The top end of the bracket 28 is secured to the piece of material 26 by a rivet 29 and the bottom end of the bracket 28 is secured to the post 11 at a point below the bolt 27 by a bolt 30.

The operation of the device is as follows:

When it becomes necessary to reach high parts on the machine 10 the steps 22 are pivoted to their horizontal position. In this position the walls 21 will strike the bottom edge of the lug 18 and hold the arms 19 against pivoting downwards beyond the horizontal. The operator then steps upon the step 25 and up onto the step 22 to reach the aforementioned high part.

When finished the operator comes down off the step 22 by first stepping on the step 25 and then down to the ground. The step 22 is pushed vertically upwards to assume a position as shown in Fig. 2 in which it will be inclined slightly rearwards and rest against the top corner of the support 13. This rearward inclination will hold the step 22 in its inoperative position against the force of gravity which will tend to tilt the step slightly forward.

In the modification of the invention shown in Figs. 6 to 9, the step construction is formed with an auxiliary step beneath the step 22 to replace the step 25 used in the previous form of the invention.

Each of the lugs 18' is formed with a forwardly and downwardly extended projection 31 upon the bottom end of which a bottom arm 32 is pivotally supported by a pin 33'. An auxiliary step 33 is extended across the top face of the bottom arms 32. The auxiliary step 33 is positioned slightly to the front of the front edge of the step 22.

Links 34 connect the front ends of the arms 19 with the front ends of the arms 32. Each link 34 has its top end pivotally connected to a lug 35 formed on the front end of its respective arm 19 by means of a pin 36. The bottom end of each link 34 is pivotally connected by an upwardly extending lug 37 formed on its respective bottom arm 32 by a pin 38.

The links 34 act to support the bottom arms 32 with relation to the arms 19 and prevent the

arms 32 from pivoting downwards past a horizontal. These links 34 also cause the steps to move in unison from an inoperative to an operative position and vice versa. The inoperative position of the steps 22 and 33 is illustrated by dot and dash lines in Fig. 7.

In other respects this form of the invention is similar to that previously described and like reference numerals identify like parts in each of the several views.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new and desire to secure by United States Letters Patent is:

A step construction for an embroidery machine, comprising a bracket fixedly mounted on the side of said machine and having a forwardly projecting, vertical lug; a top arm pivotally mounted on said lug to move in vertical planes forwards and rearwards of said machine, a step mounted on said arm, means for limiting pivoting of said arm from a horizontal position on one side of the pivot of said arm upwards to a rearwardly inclined position in which the center of gravity of said arm and step will be on the other side of the pivot of said arm, a downwardly and forwardly extending projection formed on said bracket, a bottom arm pivotally mounted on said projection to move in a vertical plane forwards and rearwards of said machine, a bottom stem mounted on said bottom arm, a rearwardly inclined link having its ends pivotally connected to the outer extremities of said arms, said pivot of said bottom arm being forwards of the pivot of said top arm and the combined length of the distance between the pivot of said bottom arm and the pivot of the bottom end of said link plus the length of said link is greater than the combined length of the distance between the pivots of said arms plus the distance between the pivot of said top arm and the pivot of the top end of said link, so that when said top arm is raised to its rearwardly inclined position said bottom arm will be raised to a substantially vertical position over its respective pivot so that the weight of said bottom arm and bottom step will exert itself substantially vertically downwards so that the greater portion of the weight will be supported by the pivot of said bottom arm.

ANTHONY MAJORIE.
